UNITED STATES PATENT OFFICE.

JAMES H. WHITE, OF McDONOUGH, NEW YORK.

MACHINE FOR DISTRIBUTING INSECT-POWDER, &c.

SPECIFICATION forming part of Letters Patent No. 400,279, dated March 26, 1889.

Application filed September 21, 1888. Serial No. 285,973. (No model.)

To all whom it may concern:

Be it known that I, JAMES H. WHITE, a citizen of the United States, residing at McDonough, Chenango county, New York, have 5 invented certain new and useful Improvements in Machines for Distributing Insect-Powder, Fertilizers, &c., of which the following is a specification.

The object of the first part of my invention to is to provide a machine for distributing insect-powder, fertilizers, &c., either continuously or intermittently.

To this end my invention consists in providing a hopper or hoppers having feeding 15 devices connected by intermediate gearing with the carrying-wheels of the machine, said gearing being so arranged that the feeding devices may be actuated either continuously or intermittently. In this connection my invention also consists in novel means for throwing 20 different parts of the gearing into or out of gear.

The object of the next part of my invention is to provide novel means for adjusting the 25 height of the distributors. To this end my invention consists in pivoting the frame of the machine on the carrying-axle and connecting the front end of the frame to the thills or shafts by means of a plate having a 30 curved slot in which works an adjusting-screw.

The object of the next part of my invention is to provide the machine with land-markers, 35 for use in making the rows in which the crops are planted. To this end my invention consists in providing hangers carrying marking-wheels at their lower ends and hinged at their upper ends to the axle of the machine. In this connection my invention also consists 40 in arranging the markers in relation to the carrying-wheels to permit of the wheels being guided by the wheel-tracks previously formed, and yet mark the land at regular intervals.

The object of the next part of my invention 45 is to provide means for more thoroughly distributing the powder from the hoppers. To this end my invention consists in forming the hopper with a concave bottom and mounting in the hopper a cylindrical series of brushes 50 formed of twisted wires carrying bristles.

In the accompanying drawings, Figure 1 is

a plan view of my improved mechanism. Fig. 2 is a vertical central section on the line 2 2 of Fig. 1. Fig. 3 is a vertical central section through one of the hoppers. Fig. 4 is a bottom view of one of the hoppers, showing also the manner of adjusting the gear-wheel on the agitator-shaft; and Fig. 5 is a perspective view of the gear-wheel for giving the agitators either a continuous or an intermittent movement. Fig. 6 is a detail enlarged view of my improved brush-agitator.

The carrying-wheels A are mounted on an axle, B, which supports the main frame or body C and revolves in bearings thereon. 65 One of the wheels is fast on the axle, the other being free to revolve thereon. As shown in the drawings, the body C preferably consists of a rectangular frame, the side beams, c, being connected to the axle by means of 70 clips c', which allow the frame to be tilted or adjusted when desired. The end beams, c², connect the side beams, and also connect the middle beams, c³, which are parallel with the side beams and are arranged at equal distances from each side.

The shafts are connected to the frame by means of plates D on the inner side of each beam, near its front end, and projecting downwardly below the frame, as shown in Fig. 2. 80 The plates are provided with curved slots d, through which extend bolts d', provided with adjusting-nuts, so that the bolts may be set at any desired position in the slot. The bolts d' are secured to the shafts E near their inner 85 ends. The shafts E are pivoted at e to hangers secured to the front beam, c². By adjusting the bolts in the slots the frame may be tilted relatively to the shafts, and thus the height of the distributors at the rear end of 90 the frame may be varied. The seat F is carried on standards G, extending rearwardly from the shafts, as shown.

The hoppers H are mounted in the rear end of the frame, on opposite sides thereof, 95 between the side beams, c, and the middle beams, c³. The form of the hoppers is shown in cross-section in Fig. 3. The hoppers are similar in construction. The description of one of them will therefore be sufficient. The 100 hopper is preferably square at the top and gradually tapering at the bottom, where it is

made concave. The bottom of the hopper is provided with a longitudinal opening, h , the width of which may be varied by plates h' , provided with slots h^2 , through which extend 5 adjusting-screws h^3 , working in the bottom or sides of the hopper. A fine wire-cloth or other reticulated material is arranged over the openings h , to deliver the powder in a finely-divided condition. Within the hopper 10 is arranged an agitator for helping the powder through the opening h . Preferably I construct the agitator of disks I, rigidly secured to the agitator-shaft J, which extends longitudinally through the bottom of the hopper. 15 The disks are arranged at each end of the hopper, and between the disks, at their outer edges, are stretched supports for the agitator-brushes. Preferably these supports consist of two or more wires, i , twisted together, and 20 the bristles i' are twisted in with the wires, so as to project therefrom, as shown in Fig. 3. When the agitator is revolved, the bristles work on the wire-gauze and loosen the powder and carry it into the opening at the bottom of the hopper, forcing it through the gauze. 25 Each hopper is provided with an agitator such as above described, and the agitators are connected by a shaft, J, extending from one side beam, c , to the other, in which it has 30 its bearings, as well as in the middle beams, c^3 . On the axle B, preferably near the middle, is mounted a large cog-wheel, K, connected to the axle by a tongue-and-groove joint, as shown, so that it may be moved longitudinally thereon. The wheel K is provided with 35 a hub, k , to which is connected one end of a lever, L, pivoted to a cross-piece, l , on the main frame and provided with an operating-handle, l' , on its outer end. By means of the 40 lever L the cog-wheel K may be moved longitudinally along the axle B for a purpose presently explained. 45 On a shaft, M, which is mounted in bearings m in the middle beams, c^3 , is secured a small cog-wheel, N, which when in operation gears with the large cog-wheel K. On the same shaft is secured a cog-wheel, O, of an improved construction. As shown in 50 Figs. 1 and 5, the cog-wheel O is provided on one side with teeth extending entirely around 55 its periphery, while on the opposite side the teeth extend only part way around, being cut away or recessed at o . The cog-wheel O gears with a smaller cog, P, on the agitator-shaft J. 60 This wheel P is provided with a hub, p , having an adjusting-screw, p' , by which it may be set at any desired position on the shaft J. It may be set to gear with that side of the 65 cog-wheel O having a continuous series of teeth, so as to cause the agitator-shaft to revolve continuously, or it may be set to gear with that side of the cog having a broken series of teeth, so as to cause the agitators to revolve intermittently. 70 65 The hoppers are arranged to deliver the powder to two rows of the plants at once, the carrying-wheels passing between these rows

and two adjacent rows on each side. When the machine is used to scatter powder on plants arranged in continuous rows, the agitators are made to work continuously; but when used to distribute the powder to plants arranged in hills the agitators are arranged to work intermittently to deliver the powder at proper intervals. 75

To the axle B are connected land-markers Q. These markers preferably consist of toothed wheels q , journaled in the lower ends of the hangers q' by means of bolts q^2 . Each pair of hangers preferably consists of two 80 rods, q^3 , embracing the axle at their upper ends close to the beams c and c^3 , and inclined inwardly and joined at their lower ends by the bolts q^2 . The markers are arranged so that the distance of one marker from the adjacent carrying-wheel is just one-fourth the entire distance between the wheels. By this arrangement, when marking the land, the tracks made by the wheels during a previous 85 traverse of the land may be used as guides in a subsequent trip, and yet the rows be kept straight and even and an equal distance apart. These markers are of course not used when the machine is distributing powder; but by my improvements the same sulky may be 90 used to mark the land and to distribute insect-powder or fertilizer. 95

I would state that, so far as part of my invention is concerned, the number of hoppers may be varied and other kinds of agitators 100 than those shown may be employed.

Having thus described my invention, what I claim as new, and desire to secure by Letters Patent of the United States, is—

1. The combination, substantially as hereinbefore set forth, of the carrying-wheels, the axle, the main frame or body mounted thereon and free to rock in bearings on the axle, the hopper on the rear end of the frame, the shafts connected to the front end of the frame, 105 the downwardly-extending plates secured to the side beams of the frame and having curved slots, and the bolts adjustable in the slots and connecting the rear ends of the shafts with the plates. 110

2. The combination, substantially as hereinbefore set forth, of the frame or body, the carrying-wheels, their axle mounted in bearings in the frame or body, the cog-wheel mounted on the axle and adjustable longitudinally thereon, the hopper on the rear end of the frame, the agitator therein, the agitator-shaft, and gearing between the agitator-shaft and the cog-wheel on the main axle. 115

3. The combination, substantially as hereinbefore set forth, of the main frame or body, the carrying-wheels, their axle, the cog-wheel mounted on the axle and adjustable longitudinally thereon, the hopper on the rear end of the frame, the agitator within the hopper, 120 and the agitator-shaft, the cog-wheel longitudinally adjustable on said shaft and gearing between the cog-wheel on the agitator-shaft and the cog-wheel on the main axle. 125

4. The combination, substantially as hereinbefore set forth, of the main frame or body, the carrying-wheels, their axle, the cog-wheel longitudinally adjustable on the axle, the hopper on the rear end of the frame, the agitator therein, the agitator-shaft, the cog-wheel on the agitator-shaft, the small cog-wheel engaging with the cog on the main axle, the shaft to which it is secured, and the cog-wheel on said shaft, provided with a continuous series of teeth on one side of its periphery and a broken series of teeth on its opposite side, for the purpose specified.
5. The combination, substantially as hereinbefore set forth, of the hopper having a longitudinal opening at its lower end, the agitator-shaft extending longitudinally through the hopper, the disks mounted thereon, the twisted wires stretched between the disks, and the bristles twisted in with the wires.

In testimony whereof I have hereunto subscribed my name.

JAMES H. WHITE.
